DEMONSTRATING DEVICE FOR VACUUM
CLEANERSArchibald J. Chapman, Grosse Pointe, Mich., as-
signor to Eureka Williams Corporation, a cor-
poration of Michigan

Application September 25, 1944, Serial No. 555,689

9 Claims. (Cl. 35—13)

1

This invention relates to exhibiting and demonstrating devices for vacuum cleaners and has particular reference to a new and improved device for exhibiting and demonstrating a vacuum cleaner in a very convenient and effective manner.

A principal object of the invention is to provide a new and improved device for exhibiting and demonstrating a vacuum cleaner.

Other objects and advantages of the invention will be apparent from a consideration of the following specification taken in conjunction with the accompanying drawing, of which there is one sheet and wherein:

Fig. 1 is a perspective view of the device embodying the invention;

Fig. 2 is a side elevational view thereof with the case removed in order to illustrate the working parts of the mechanism and taken generally along the line 2—2 of Fig. 1; and

Fig. 3 is a fragmentary sectional view taken generally along the line 3—3 of Fig. 1.

The device comprises in general a unit having a vacuum cleaner 10 positioned thereon. The unit includes a suitable case 12 enclosing a base 14 upon which a plurality of drums 16, 18, 20 and 22 are rotatably mounted, the drums 16 and 22 having their shafts journaled in bearings 24 which are adjustably mounted in a suitable bearing retainer 26. Rollers 30 and 32 positioned close together with their axes arranged parallel are arranged above the drums 18 and 20. An endless strip of carpeting 34 is arranged on the drums 20 and 22 and the roller 32, while another endless strip of carpeting 36 is arranged on the drums 16 and 18 and the roller 30. The two strips of carpeting are arranged in alignment and each has upper horizontally extending portions or runs extending between the roller 32 and the drum 22 and the roller 30 and the drum 16 respectively. Such horizontal portions are visible through opening 38 provided in the upper surface of the case 12, and the cleaner 10 is arranged as illustrated to straddle the joint or break between the horizontally extending portions of the strips 34 and 36 of carpeting.

The width of the nozzle of the cleaner 10 may be slightly greater than that of the opening 38 so that the ends of the cleaner will rest upon the top of the case 12 at the side of the opening 38, and a bar 42 spanning the opening 38 beneath the cleaner 10 may be provided for supporting the rear end of the cleaner above the strips of carpeting 34 and 36.

The drums 18 and 20 are provided with sprock-

2

ets 44. A sprocket 46 driven through a suitable speed-reducing mechanism from an electric motor 48 drives a chain 50 which is operatively in engagement with the teeth of the sprockets 44 for driving the same during the operation of the motor.

A rotary beater 52 having axially extending beaters 54 is journaled beneath the horizontally extending run of the carpet 34, and this beater 52 is connected by a belt and pulley drive 55 to one of the sprockets 44 so that during operation of the motor the beater 52 will be driven.

The beater 52 is arranged to beat the under side of the carpet 34 a short distance ahead of the front of the cleaner 10 so as to make the carpet vibrate at the region immediately in front of the cleaner 10. The carpet 34 has permanently secured to the exposed surface thereof suitable material 60 of a cotton or liny nature so as to simulate the appearance of a dirty carpet. The carpet 36 must be of the same character and color as the carpet 34 but is clean and free from lint, dirt, etc.

During the operation of the motor 48 the pulley 26 44 will be driven in a counterclockwise direction so as to drive the strips 34 and 36 of carpeting in the direction indicated by the arrows in Fig. 2. This will give the appearance of a dirty carpet passing under the nozzle of the cleaner and a clean carpet moving away from the back end of the cleaner. The action of the beater 52 at this time will simulate the action of the brush or agitator of the cleaner in beating the carpet. The horizontal run of the carpet 36 may pass over a flat solid surface 65 so as to eliminate the possibility of this part of the carpet vibrating during the operation of the device.

The motor of the vacuum cleaner may be turned on during the operation of the device if desired, although it is not necessary. In order to give a more realistic appearance to the cleaner if the same is not operated during the operation of the device, the bag of the cleaner may be fixed in a distended position by any suitable means 45 so as to give the appearance of a vacuum cleaner bag during normal cleaner operation.

One of the principal advantages inherent in this device is that with it it is possible to provide a demonstration in a store without the use 50 of an operator.

While the invention has been described with some detail, it is to be understood that the description is for the purpose of illustration only and is not definitive of the limits of the inventive idea. The right is reserved to make such

changes in the details of construction and arrangement of parts as will fall within the purview of the attached claims.

I claim:

1. A device for exhibiting suction cleaners comprising a piece of carpeting arranged so as to have an exposed horizontally extending portion, said piece of carpeting having litter or dirt secured thereto, a second piece of clean carpeting arranged so as to have an exposed horizontally extending portion in line with and adjoining that of said first-mentioned piece of carpeting, a suction cleaner overlying the gap between the horizontally extending portions of said pieces of carpeting and having its nozzle arranged over and presented toward said first-mentioned piece, and means for moving both of said pieces of carpeting relative to said cleaner at substantially the same speed and in a direction corresponding with movement from front to rear of said cleaner.

2. A device for exhibiting suction cleaners comprising a piece of carpeting arranged so as to have an exposed horizontally extending portion, said piece of carpeting having litter or dirt secured thereto, a second piece of clean carpeting arranged so as to have an exposed horizontally extending portion in line with and adjoining that of said first-mentioned piece of carpeting, a suction cleaner overlying the gap between the horizontally extending portions of said pieces of carpeting and having its nozzle arranged over and presented toward said first-mentioned piece, means for moving both of said pieces of carpeting relative to said cleaner at substantially the same speed and in a direction corresponding with movement from front to rear of said cleaner, and means below the carpeting operative for beating the horizontally extending portion of the first-mentioned piece of carpeting in a zone adjacent the nozzle of said cleaner and simultaneously with movement of said carpeting cleaner.

3. A device for exhibiting suction cleaners comprising an endless piece of carpeting arranged on rolls so as to have an exposed horizontally extending portion, said piece of carpeting having litter or dirt secured thereto, a second endless piece of clean carpeting arranged on rolls so as to have an exposed horizontally extending portion in line with and adjoining that of said first-mentioned piece of carpeting, a suction cleaner overlying the gap between the horizontally extending portions of said pieces of carpeting and having its nozzle arranged over and presented toward said first-mentioned piece, and means for moving both of said pieces of carpeting relative to said cleaner at substantially the same speed and in a direction corresponding with movement from front to rear of said cleaner.

4. A device for exhibiting suction cleaners comprising an endless piece of carpeting arranged on rolls so as to have an exposed horizontally extending portion, said piece of carpeting having litter or dirt secured thereto, a second endless piece of clean carpeting arranged on rolls so as to have an exposed horizontally extending portion in line with and adjoining that of said first-mentioned piece of carpeting, a suction cleaner overlying the gap between the horizontally extending portions of said pieces of carpeting and having its nozzle arranged over and presented toward said first-mentioned piece, means for moving both of said pieces of carpeting relative to said cleaner at substantially the same speed and in a direction corresponding with movement from front to rear of said cleaner, and means

for beating the horizontally extending portion of the first-mentioned piece of carpeting in a zone adjacent the nozzle of said cleaner and simultaneously with movement of said carpeting.

5. A device for exhibiting suction cleaners comprising an endless piece of carpeting arranged on rolls so as to have an exposed horizontally extending portion, said piece of carpeting having litter or dirt secured thereto, a second endless piece of clean carpeting arranged on rolls so as to have an exposed horizontally extending portion in line with and adjoining that of said first-mentioned piece of carpeting, a suction cleaner overlying the gap between the horizontally extending portions of said pieces of carpeting and having its nozzle arranged over and presented toward said first-mentioned piece, means for moving both of said pieces of carpeting relative to said cleaner at substantially the same speed and in a direction corresponding with movement from front to rear of said cleaner, and means beneath the horizontally extending portion of the first-mentioned piece of carpeting for beating the same adjacent the nozzle of the cleaner and simultaneously with movement of said carpeting.

6. A device for exhibiting suction cleaners comprising an endless piece of carpeting arranged on rolls so as to have a horizontally extending portion, said piece of carpeting having litter or dirt secured thereto, a second endless piece of clean carpeting arranged on rolls so as to have a horizontally extending portion in line with and adjoining that of said first-mentioned piece of carpeting, a casing enclosing said carpeting and having an elongated opening in the upper surface thereof through which said horizontally extending portions are exposed, a suction cleaner overlying the gap between the horizontally extending portions of said pieces of carpeting and having its nozzle arranged over and presented toward said first-mentioned piece, means within said casing for moving both of said pieces of carpeting relative to said cleaner at substantially the same speed and in a direction corresponding with movement from front to rear of said cleaner.

7. A device for exhibiting suction cleaners comprising an endless piece of carpeting arranged on rolls so as to have a horizontally extending portion, said piece of carpeting having litter or dirt secured thereto, a second endless piece of clean carpeting arranged on rolls so as to have a horizontally extending portion in line with and adjoining that of said first-mentioned piece of carpeting, a casing enclosing said carpeting and having an elongated opening in the upper surface thereof through which said horizontally extending portions are exposed, a suction cleaner overlying the gap between the horizontally extending portions of said pieces of carpeting and having its nozzle arranged over and presented toward said first-mentioned piece, means within said casing for moving both of said pieces of carpeting relative to said cleaner at substantially the same speed and in a direction corresponding with movement from front to rear of said cleaner, and means for beating the horizontally extending portion of the first-mentioned piece of carpeting in a zone adjacent the nozzle of said cleaner.

8. A device for exhibiting suction cleaners comprising carpeting arranged on rolls so as to have an exposed horizontally extending portion, a suction cleaner having a nozzle overlying and presented toward the horizontally extending portion of said carpeting, and means for moving said carpeting relative to said cleaner in a direction

corresponding with movement from front to rear of said cleaner.

9. A device for exhibiting suction cleaners comprising carpeting arranged on rolls so as to have an exposed horizontally extending portion, a suction cleaner having a nozzle overlying and presented toward the horizontally extending portion of said carpeting, means for moving said

carpeting relative to said cleaner in a direction corresponding with movement from front to rear of said cleaner, and means for beating the horizontally extending portion of said carpeting adjacent the nozzle of said cleaner and during movement of said carpeting.

ARCHIBALD J. CHAPMAN.
